UNITED STATES PATENT OFFICE

148,242

DESIGN FOR A BREAKFAST NOOK

William F. Horsewood, Pomona, Calif.

Application August 23, 1946, Serial No. 132,777

Term of patent 14 years

(Cl. D15—11)

To all whom it may concern:

Be it known that I, William F. Horsewood, a citizen of the United States, residing at Pomona, in the county of Los Angeles and State of California, have invented a new, original, and ornamental Design for a Breakfast Nook, of which the following is a specification, reference being had to the accompanying drawing, forming a part thereof.

I claim:

The ornamental design for a breakfast nook, as shown.

WILLIAM F. HORSEWOOD.
